ELECTRON DISCHARGE TUBE CIRCUITS FOR
GENERATING ELECTRICAL OSCILLATIONS
OF SAW-TOOTH WAVE FORM

Keith Gorden Huntley, Harlington, Hayes, England, assignor to Electric & Musical Industries Limited, Hayes, Middlesex, England

Application August 24, 1950, Serial No. 181,136
In Great Britain September 22, 1949

8 Claims. (Cl. 175—335)

1

This invention relates to electron discharge tube circuits for generating oscillations of saw-tooth waveform. Such circuits are used for example in television for the purpose of reflecting the beam of a cathode ray tube.

In a known circuit two tubes are employed for generating the long flank of the sawtooth oscillations, one of the tubes being conducting for one portion of said long flank and the other tube being conducting for the other portion of the long flank. A type of circuit which employs two tubes in this manner is one which operates on the resonant return principle in which a sawtooth current is set up in inductive scanning coils associated with a cathode ray tube and in which the short flank of the sawtooth oscillations is obtained by allowing the current in the coils to execute a free half-cycle of oscillation at the end of the long flank of the sawtooth oscillation. In such a circuit one of the aforesaid tubes is employed to prevent further free oscillation by becoming conducting, this tube during its conducting period generating the initial portion of the long flank of the sawtooth oscillation after which the other tube becomes conducting for generating the remaining portion of the long flank. In this resonant return type of circuit, the tube which prevents further oscillation is usually called the damper tube and the other tube is usually called the driver tube since this latter tube has applied thereto suitable controlling voltages which serve to render the valve conducting in an appropriate manner for the generation of the sawtooth oscillations. In some circuits of this type when employed for generating oscillations at line frequency in a television receiver the driver tube may be non-conducting for as much as the first 50 per cent of the long flank of the generated oscillation. It is of course well recognised that it is desirable for the long flank of the generated oscillations to be linear throughout its whole stroke but it is found with the circuits described above that the initial portion of the long flank is somewhat curved.

In the United States co-pending Application Serial No. 128,598, filed November 21, 1949 by J. E. Best and R. C. White, circuits are disclosed for making the initial portion of the long flank more linear. The present invention seeks to provide improvements in said circuits.

In order that the invention may be clearly understood and readily carried into effect, it will now be more fully described with reference to the accompanying drawing, in which Figure 1 illustrates an embodiment of the present invention

2

tion and Figure 2 illustrates a part of the circuit shown in Figure 1 embodying a modification.

The drawing illustrates a circuit according to the invention which operates on the resonant return principle and mainly differs from the circuits shown in Figures 1 and 2 of the drawings of said co-pending application in that the negative feedback voltage for linearising both the initial and subsequent portions of the long flank of the generated sawtooth oscillations is a voltage which is substantially proportional to the voltage set up across the inductive load. The circuit shown herein also illustrates an arrangement for generating controlling voltages which in this case, in the absence of negative feedback, are substantially constant voltages but which are modified by the negative feedback voltage to set up substantially sawtooth voltages for application to the driver and damper tubes.

As shown in Figure 1 in the drawing the reference numeral 13 illustrates the driver tube and the reference numeral 14 the damper tube. The driver tube 13 is a tetrode and its anode is connected to the positive terminal of a source of anode current indicated at 15 through a resistance 16, which serves to suppress parasitic oscillations, the primary winding 17 of a transformer and a decoupling resistance 18 which is decoupled to earth by a condenser 19. The secondary winding 20 of the transformer feeds current to the scanning coils 21 through a resistance 22, the resistance of the scanning coils being indicated by the resistance 23. The damper tube 14 is shunted across the scanning coils 21, and is shown as a triode. Control voltages are applied to the control electrodes of the tubes 13 and 14, said control voltages being derived from a double triode tube 24. The tubes 13 and 14 have their cathodes connected to earth through resistances 25 and 26 respectively which serve to make the characteristics of said tubes more linear. The common cathode of tube 24 is connected through a resistance 27 to a source of negative potential, the resistance 27 serving to cause the tube 24 to function as a push-pull cathode coupled amplifier. Assuming that the scanning coils 21 were ideal and that the tubes 13 and 14 were also ideal i. e. have zero internal impedance, then the voltage across said coils, in order to set up a truly linear sawtooth current in the coils, would be a constant voltage so that the control voltages derived from the tube 24 and which are fed to the control electrodes of the tubes 13 and 14 would, in this case, be constant and no negative feedback voltage would be required. However,

the scanning coils do not represent an ideal inductance and the tubes possess internal impedance and, accordingly, the control voltages applied to the tubes 13 and 14 are modified by a negative feedback voltage, such negative feedback voltage being substantially proportional to the voltage set up across said scanning coils. The negative feedback voltage is derived, as shown, from the upper end of the scanning coils 21, and is applied through condenser 28 and through a resistance 29 to one of the control electrodes of the tube 24. The other control electrode of the tube 24 is connected to earth through a resistance 30. The junction between the condenser 28 and resistance 29 is connected to a resistance 31 to earth through a decoupling condenser 32, the junction point of the resistance 31 and condenser 32 being connected to a tapping point on a potentiometer 33 which is connected across a source of D. C. potential. The condenser 28 and resistance 31 form a time constant circuit in the feedback path feeding the voltage derived from the upper end of the scanning coils 21 to the tube 24 so as to impart a correct shape to this feedback voltage to compensate for the resistance 23 of the scanning coils and thus obtain the required linearity of sawtooth current set up in the scanning coils 21. For this purpose the components are designed so that $C_{28}R_{31} = L_{21}/R_{23}$. The tapping point on the potentiometer 33 is adjustable for the purpose of varying the slope of the sawtooth current. The tube 24 functions as a push-pull amplifier and the control voltages which are set up in the anode circuits of the tube 24 are applied as aforesaid to the control electrodes of the tubes 13 and 14. The anode 34 of the tube 24 is connected to the source of positive potential 15 through resistances 35 and 36, the junction point of the resistances 35 and 36 being decoupled to earth through a condenser 37. The anode 34 is connected to the control electrode of the tube 13 through a rectifier 38 which may be a contact rectifier or a rectifier of some other suitable form and a resistance 39 which is shunted by a bypass condenser 40, the control-electrode circuit of the tube 13 including a resistance 41 and a resistance 42 to the junction of which the resistance 39 is connected, whilst the lower end of the resistance 42 is connected to a tapping point on a resistance 43 one end of which is connected to the negative terminal of a source of bias voltage whilst the other end is earthed, the resistances 39, 42 and 43 serving to maintain the control electrode of the tube 13 at an appropriate potential. Between the rectifier 38 and the anode 34 a condenser 44 is provided which is connected to earth, as shown, the purpose of which will be hereinafter referred to. The anode 45 of the tube 24 is connected to the source of anode potential 15 through resistances 46 and 47 the junction point of which is decoupled to earth through a condenser 48. The anode 45 is connected to the control electrode of the tube 14 through a resistance 49 shunted by a bypass condenser 50, the resistance 49 being connected to the junction of a resistance 51 and a resistance 52, the other end of the latter being connected to a source of negative potential, the resistances 49 and 52 serving to apply an appropriate biasing potential to the tube 14. The potential for the screening electrode of the tube 13 is derived from the positive potential source 15 through a resistance 53, the screening electrode being decoupled to the cathode of the tube 13 through condenser 54. The circuit shown is syn-

chronised by applying to the control electrode of the tube 13 synchronising pulses which are set up at the anode of a tube 55 which may be the output tube of a multivibrator or other source of pulses, the anode of the tube 55 deriving its anode potential from a resistance 56 connected to the junction point of the resistances 35 and 36. The condenser 44 serves to prevent undesired oscillations which may be otherwise set up due to phase shift in the feedback network and the rectifier 38 serves to isolate the condenser 44 from the tube 55 when a pulse is set up at the anode of said tube so as to prevent delay in the building up of the leading edge of the pulse which would otherwise occur owing to the absorption of pulse energy by the condenser 44. This serves to prevent an increase in the duration of the return stroke of the sawtooth oscillations.

When the tube 13 is conducting, current is fed to the scanning coils 21 and the damper tube 14 during this period is non-conducting. When a pulse is applied to the control electrode of the tube 13 from the tube 55, the tube 13 is rendered non-conducting and the current in the scanning coils 21 is then permitted to execute a half-cycle of oscillation after which the tube 14 becomes conducting to permit the generation of the initial portion of the long flank of the sawtooth current across the coils 21, this portion of the long flank being controlled and linearised by the negative feedback voltage fed to the tube 24. This feedback voltage is of course amplified by the tube 24 and serves to reduce the effective impedance of the tube 14 so that a substantially linear current flows through the coils 21. The D. C. bias applied to the tube 13 is so adjusted that before the tube 14 is rendered non-conducting the tube 13 becomes conducting so as to generate the subsequent portion of the long flank of the sawtooth current. This subsequent portion is also linearised due to the negative feedback which is amplified by the tube 24 and fed from the anode 34 to the control electrode of tube 13. Upon the occurrence of a further pulse from the tube 55, the tube 13 is rendered non-conducting and the cycle recommences.

The resistance 46 is made considerably smaller than the resistance 35 so that a greater degree of control will be exercised by the tube 13 with the result that the tube 14 will be rendered non-conducting relatively slowly so as to ensure that the tube 14 will always present a sufficiently low impedance across the scanning coils 21 to prevent undesired oscillations from occurring.

The circuit shown in Figure 1 may be modified as shown in Figure 2 by providing a resistance 57 in the anode circuit of the tube 14 and then connecting the upper end of the scanning coils 21 to the junction of the resistance 57 and the anode of the tube 14. The resistance 57 is made equal to the effective anode resistance of the tube 14, i. e., the actual anode resistance divided by the gain of the feedback loop so that the upper end of the coils 21 is then effectively a point of zero impedance thus further improving the linearity of the generated sawtooth oscillations.

What I claim is:

1. A circuit for generating oscillations of sawtooth waveform in a load, comprising a pair of tubes each having a control electrode, a source of control voltage, means for applying a control voltage from said source to one of said tubes to control the generation of the initial portion of the long flank of a sawtooth oscillation, means

for applying a control voltage from said source to the other tube to control the subsequent portion of said long flank, a connection from said load to provide a negative feedback voltage substantially proportional to the voltage set up across said load, said source of control voltage including a constant voltage, and means for obtaining the difference between said negative feedback voltage and said constant voltage to derive said control voltage modified to linearize both the initial and subsequent portions of said long flank.

2. A circuit for generating oscillations of sawtooth waveform in an inductive load, comprising a driver tube having a control electrode, means for rendering said tube conducting to set up a portion of the long flank of a sawtooth oscillation in said load, means for interrupting the current in said load to produce a free half cycle of oscillation of said current for generating the short flank of said sawtooth oscillation, a damper tube connected across said load to prevent further free oscillation and to generate a further portion of said long flank, said damper tube having a control electrode, a source of control voltage, means to provide a negative feedback voltage substantially proportional to the voltage set up across said load, said source of control voltage including a constant voltage, means for obtaining the difference between said negative feedback voltage and said constant voltage to derive said control voltage, and means for applying said control voltage to the control electrodes of said driver and damper tubes to linearize both said portions of said long flank.

3. A circuit for generating oscillations of sawtooth waveform in a load, comprising a pair of tubes each having a control electrode, a source of control voltage, means for applying a control voltage from said source to one of said tubes to control the generation of the initial portion of the long flank of a sawtooth oscillation, means for applying a control voltage from said source to the other tube to control the subsequent portion of said long flank, said source including a push-pull amplifier for generating said control voltage, a connection from said load to said amplifier to provide a negative feedback voltage substantially proportional to the voltage set up across said load, means for applying said feedback voltage to said amplifier to obtain a control voltage dependent on the difference between said negative feedback voltage and a constant voltage, and means for applying said control voltage in push-pull to said tubes to linearize both the initial and subsequent portions of said long flank.

4. A circuit for generating oscillations of sawtooth waveform in an inductive load, comprising a driver tube having a control electrode, means for rendering said tube conducting to set up a portion of the long flank of a sawtooth oscillation in said load, means for interrupting the current in said load to produce a free half cycle of oscillation of said current for generating the short flank of said sawtooth oscillation, a damper tube connected across said load to prevent further free oscillation and to generate a further portion of said long flank, said damper tube having a control electrode, a source of control voltage including a push-pull amplifier, means coupling said load to said source to provide a negative feedback voltage substantially proportional to the voltage set up across said load, means for applying said feedback voltage to said amplifier to obtain a control voltage dependent on the difference between said negative feedback volt-

age and a constant voltage, and means for applying said control voltage in push-pull to said tubes to linearize both said portions of said long flank.

5. A circuit for generating oscillations of sawtooth waveform in an inductive load which includes a resistive component, comprising a driver tube having a control electrode, means for rendering said tube conducting to set up a portion of the long flank of a sawtooth oscillation in said load, means for interrupting the current in said load to produce a free half cycle of oscillation of said current for generating the short flank of said sawtooth oscillation, a damper tube connected across said load to prevent further free oscillation and to generate a further portion of said long flank, said damper tube having a control electrode, a source of control voltage, means coupling said load to said source to provide negative feedback voltage substantially proportional to the voltage set up across said load, said source of control voltage including a constant voltage, means for obtaining the difference between said negative feedback voltage and said constant voltage to derive said control voltage, and means for applying said control voltage to the control electrodes of said driver and damper tubes to linearize both said portions of said long flank, said coupling means including a time constant network to compensate for the resistive component of said load.

6. A circuit for generating oscillations of sawtooth waveform in an inductive load which includes a resistive component, comprising a driver tube having a control electrode, means for rendering said tube conductive to set up a portion of the long flank of a sawtooth oscillation in said load, means for interrupting the current in said load to produce a free half cycle of oscillation of said current for generating the short flank of said sawtooth oscillation, a damper tube connected across said load to prevent further free oscillation and to generate a further portion of said long flank, said damper tube having a control electrode, a source of control voltage including a push-pull amplifier, means coupling said load to said source to provide a negative feedback voltage substantially proportional to the voltage set up across said load, means for applying said feedback voltage to said amplifier to obtain a control voltage dependent on the difference between said negative feedback voltage and a constant voltage, and means for applying said control voltage in push-pull to said tubes to linearize both the initial and subsequent portions of said long flank, said coupling means including a time constant network to compensate for the resistive component of said load.

7. A circuit for generating oscillations of sawtooth waveform in an inductive load comprising a driver tube having a control electrode, means for rendering said tube conducting to set up a portion of the long flank of a sawtooth oscillation in said load, means for interrupting the current in said load to produce a free half cycle of oscillation of said current for generating the short flank of said sawtooth oscillation, a damper tube connected across said load to prevent further free oscillation and to generate a further portion of said long flank, said damper tube having a control electrode, a source of control voltage, means coupling said load to said source to provide negative feedback voltage substantially proportional to the voltage set up across said load, said source of control voltage including a constant voltage, means for obtaining the difference between said negative feedback voltage

7 and said constant voltage to derive said control voltage, and means for applying said control voltage to the control electrodes of said driver and damper tubes to linearize both portions of said long flank, said damper tube having an anode coupled to said load through a resistance, and one end of said load being connected to the junction of said resistance and anode to maintain said end effectively at zero impedance.

3. A circuit for generating oscillations of saw-tooth waveform in an inductive load comprising a driver tube having a control electrode, means for rendering said tube conducting to set up a portion of the long flank of a sawtooth oscillation in said load, means for interrupting the current in said load to produce a free half cycle of oscillation of the current for generating the short flank of said sawtooth oscillation, a damper tube connected across said load to prevent further free oscillation and to generate a further portion of said long flank, said damper tube having a control electrode, a source of control voltage including a push-pull amplifier, means coupling said load to said source to provide a negative feedback voltage substantially proportional to the voltage set up across said load, said source of control voltage including a constant voltage, means for obtaining the difference between said negative feedback voltage and said constant voltage to derive said control voltage, 10 and means for applying said control voltage in

15 push-pull to said tubes to linearize both said portions of said long flank, said damper tube having an anode coupled to said load through a resistance, and one end of said load being connected to the junction of said resistance and anode to maintain said end effectively at zero impedance.
